UNITED STATES PATENT OFFICE.

JOSEPH C. BREWER, OF COLUMBUS, GEORGIA, ASSIGNOR TO HIMSELF AND
WILLIAM H. ROBERTS & CO., OF SAME PLACE.

IMPROVEMENT IN PORTABLE FURNACES.

Specification forming part of Letters Patent No. 146,226, dated January 6, 1874; application filed
December 30, 1872.

To all whom it may concern:

Be it known that I, JOSEPH C. BREWER, of Columbus, in the county of Muscogee and State of Georgia, have invented certain new and useful Improvements in Furnaces, of which the following is a full, clear, and exact description, reference being had to the accompanying drawing and the letters of reference marked thereon, making part of this specification, in which—

Figure 1 is a front view. Fig. 2 is a transverse sectional view.

The object of my invention is the production of a cheap and practicable furnace; one that is light, portable, and adjustable, and designed, principally, to be used in the open air. The nature of my invention consists in constructing the furnace in two sections, each having, at its outer edges and at the top and bottom thereof numerous holes, by means of which, and the employment of bolts and nuts, the furnace can be adapted to the use of the largest caldron or the smallest kettle, while, at the same time, it can be so shifted as to increase or diminish the draft, and compel the smoke and sparks to be driven away from the operator or attendant.

The construction and operation of my invention are as follows: A is the furnace, which is composed of two sheets or strips, B B', of metal, boiler-iron, or other suitable material. These sheets have punched, bored, or otherwise formed, numerous holes, $b\ b'$, in their upper and lower sections, commencing from their outer edges and extending in toward their centers, and are connected together by the bolts b^1 and nuts b^2 . This construction enables the rim of the furnace to be contracted or enlarged, so that it may accommodate itself to different-sized pots and kettles. C is the door, which is cut in the lower portion of the section B, and C' is the collar for the pipe, should one be desired,

which is attached to a hole cut in the upper portion of the section B'.

When the furnace is to be transported from place to place, if desired, the two sections may be detached and one placed within the other, thus being easily carried; or, where a number of them are to be transported, compelling them to occupy but little space in the car or wagon. When large boilers or caldrons are to be heated, I usually employ a grooved bar and rollers placed on top of the rim of the furnace, and by this means I am enabled to turn the caldron around without removing it from the furnace.

One of the chief advantages of my furnace is, that it requires about one-tenth of the fuel that is now used to heat a pot or kettle in the open air, and will reach the boiling-point in about one-fourth of the time, which, with the freedom from smoke and sparks blowing into the face of the attendant, and its cheapness, makes it very desirable.

What I claim as new, and desire to secure by Letters Patent of the United States, is—

The furnace A, consisting of the sheets B B', having holes $b\ b'$ and bolts and nuts $b^1\ b^1'$ and $b^2\ b^2'$, when the sheets are entirely independent, so that one can be placed in the other for transportation or packing away; and the sheets are so arranged that, in operation, the furnace can be adjusted so as to receive a vessel of any desired size, and the bolts and nuts always securing it, so as to leave a true circular opening for said vessel, substantially as described.

In testimony whereof I have signed my name to this specification in the presence of two subscribing witnesses.

JOSEPH C. BREWER.
